UNITED STATES PATENT OFFICE

JOHN T. QUIGLEY, OF LOS ANGELES, CALIFORNIA

LABEL HOLDER FOR VERTICAL FILES

Application filed June 27, 1929. Serial No. 374,043.

The object of this invention is to simplify the construction and manner of use of label-holding clips removably attached to the upper portion of vertical file sheets, and preferably sheets having a narrow fold along the upper 5 edge.

One feature of the invention consists in making such label holder out of a small sheet of metal with an upper label-holding portion 10 and a lower portion provided with an upwardly extending tongue or tongues adapted to fit between the fold and sheet of paper and a plurality of downwardly extending tongues adapted to fit behind the upper part 15 of the sheet of paper. Such label holder is readily slipped laterally on a sheet of paper with said folded edge, and interlocks the label holder therewith against any vertical displacement, although it can be moved laterally 20 on the sheet of paper.

The label holder always rests on the upper folded edge of the vertical filing sheet and said upper edge of the vertical filing sheet prevents the downward movement of the label holder while the upwardly extending tongue 25 between the filing sheet and its fold prevents the upward movement of the label holder independently of the sheet of paper.

One feature of the invention consists in the 30 simplicity of the label holder as it is formed entirely of one sheet of metal, without folding any portion of the metal sheet upon itself.

In the drawings:

Fig. 1 is a front elevation of the vertical 35 file sheet with my label holder in place.

Fig. 2 is an edge view of the file sheet showing the folded portion at its upper end.

Fig. 3 is an enlarged fragmental edge view 40 of the file sheet and label holder attached thereto.

Fig. 4 is a front view of the label holder.

Fig. 5 is an enlarged section on line 5—5, Fig. 4, showing a detail of the label bed plate.

Fig. 6 is an enlarged section on line 6—6, 45 Fig. 4, showing the downwardly extending tongues spaced a greater distance away from the back of the holder than the upwardly extending tongue.

Fig. 7 is a section on line 7—7, Fig. 1, showing 50 the tortuous course of the file sheet under

the downwardly extending tongues and over the upwardly extending tongue.

Fig. 8 is an enlarged fragmental section on line 8—8, Fig. 1, showing a downwardly extending tongue extended over the back of 55 the file sheet so it pinchingly engages the folded portion with the back side of the holder and also showing the base of the tongue riding on the folded edge of the file sheet so as to limit the downward movement 60 of the holder; also showing the label and transparent cover detachably secured to the bed plate.

Fig. 9 is an enlarged fragmental section on line 9—9, Fig. 1, showing the upwardly 65 extending tongue extending in between the file sheet and the folded portion so that the free end of the tongue engages the fold and prevents vertical displacement of the holder.

Fig. 10 is an enlarged section on line 10—10, 70 Fig. 4, showing a downwardly extending tongue as spaced away from the back side of the holder, also showing the relative position of the rest, flange and a detent on the label bed plate.

Fig. 11 is an enlarged section on line 11—11, 75 Fig. 4, showing the upwardly extending tongue spaced a less distance from the back of the holder than that of the downwardly extending tongue shown in Fig. 10.

Fig. 12 is a view analogous to Fig. 4, showing the holder provided with a plurality of both upwardly and downwardly extending tongues.

In the manufacture of this label holder it 80 is punched from sheet-metal in a finished form suitable for immediate use in a vertical file or so it can be immediately detachably connected to a vertical file sheet.

The sheet-metal from which the holder is 85 punched is of suitable thickness and tenacity so it will hold its proper form when finished with a sufficient resiliency to its integral tongues and detents so they can yield sufficiently when the holder is placed in use.

The holder appears to be rectangular from a front view, but in reality it comprises two rectangular plates 12 and 13 that are 90 arranged angularly toward one another and 100

are connected by an intermediate plate 14 that is preferably curved.

In the act of stamping out the holder a plurality of tongues 15, 16 and 17 are thrown backward in the same direction from the plate 12 and preferably the tongues 15 and 16 are spaced further from the back of the plate 12 than the tongue 17 and point in opposite directions. In other words the tongues 15 and 16 extend downwardly on opposite sides of the upwardly extending tongue 17 and are spaced a greater distance from the back of the plate 12 than the tongue 17. It is understood, however, that there can be a plurality of the tongues 17, as shown in Fig. 12, if so desired.

The space between the inner wall of the tongue 17 and back of wall 12 is preferably slightly less than the thickness of the file sheet 18 to which it is to be attached so the tongue 17 will engage the file sheet fold 19 with some tension when in use. Also the spaces between the inner walls of the tongues 15, 16 and wall 12 are slightly less than the combined thickness of the file sheet 18 and its fold 19 so that these tongues will also engage the file sheet and fold with some tension when in use.

The tongues 15 and 16 are arranged so that in use they engage the back side of the file sheet 18 and pinch its fold 19 up against the back side of the plate 12, and also the bases 20 of these tongues ride upon the folded edge 21 of the file sheet. The tongue 17 which is associated and coacts with the tongues 15 and 16 is preferably arranged between them and it extends upward between the file sheet 18 and its fold 19 and pinches the latter against the back wall of the plate 12. The purpose of this tongue 17, in addition to properly holding the holder on the file sheet, is to prevent displacement of the holder in lines endwise of the file sheet. In other words the point of the tongue 17 acts as a detent to prevent the holder from being moved endwise of the sheet. It extends up between the sheet and folded portion so that when the latter is lifted up the tongue engages the fold and prevents displacement.

As previously stated, I may use one or more of the tongues 17 and also as many of the tongues 15 and 16 as may be desired.

It is obvious that the label holder can be moved sidewise, the tension of the tongues being such as to permit a relatively free movement of the holder from side to side of the file sheet.

The rectangular bed plate 13 that is connected to the plate 12 by the curved plate 14, forms a bed for the label 22 and its transparent cover 23, and this plate and all of its associated parts are cut and pressed into proper form when the label holder is punched from the sheet-metal.

A wall portion 114 of the plate 14 that is

integral with the plate 13 is bent at right-angles to the latter to form a rest for the lower edges of the label and its cover; and on the opposite edge of the plate 12 is a flange 24 extending upward and arranged at right-angles to the plate 13 and the height of the flange preferably slightly exceeds the combined thickness of the label 22 and its transparent cover 23; and upper edges of the label and cover snugly engage the inside wall of the flange.

Adjacent the ends of the plate 12 are detents 25, 26 that are struck upward from the plate 13 and they are arranged parallel with the plate so as to extend over and engage the ends of the label and cover and detachably hold them in place on the bed plate 13.

Preferably the label 22 and its transparent cover 23 are sufficiently resilient to permit them to be bent so their ends can be inserted under the free ends of the detents so that when released they will straighten out and be flat on the bed plate so they will be secure from accidental displacement. It is obvious that the label and cover can be easily removed for any purpose such as changing the data thereon.

Rectangular strips of suitable material may be used for the label 22, of a width which will permit them to lie in the recess formed by the wall 114 and flange 24. The label 22 should be long enough for both ends to extend under the tongues 25, 26. A rectangular strip of thin transparent material 23 is useful as a cover with any desired kind of paper bearing the inscription; or, if desired, a strip of cardboard alone, bearing the label, may be used with good results in this construction.

The bed 13 with its right-angle side wall 114 and flange 24 and the retaining tongues 25, 26 at each end provides means whereby labeling material may be inserted quickly and easily and thereafter may not be accidentally displaced during manipulation of the file. The fingers of the operative will not dislodge the labels; the labels may be intentionally removed and replaced with great facility. This construction also provides means whereby substantially the entire surface of the bed plate 13 may be occupied by visible lettering.

From the foregoing it can readily be seen that I provide a label holder that can be formed by a single stroke of a punch that immediately is in suitable form and condition for detachably connecting it to a vertical file sheet and which when so connected is easily movable sidewise along the sheet but which cannot be displaced endwise thereto.

In use the label holder is detachably connected to a file sheet by first moving the holder sidewise to the sheet so that the top portion of the sheet and its fold will extend under one or the other of the tongues 15, 16 with

bend or base 20 of the tongue riding on the edge fold 21 of the file sheet. When the holder is moved further the center tongue 17 slides in between the file sheet 18 and fold 19 and the holder is moved further so that the other tongue will extend over the back of the file sheet as previously stated, so that the holder can be freely moved from side to side of the file sheet but cannot be displaced endwise thereto. The label and its transparent cover are attached and detached as stated.

I claim as my invention:

1. A label-holder for a vertical file sheet with a portion along its upper edge that can be folded down, consisting of a sheet of metal having the lower portion provided with an integral upwardly extending tongue adapted to project between the fold and the sheet of paper, and a plurality of downwardly extending integral tongues adapted to rest upon the upper edge and fit behind the sheet of paper, whereby the label-holder cannot be removed vertically from the filing sheet and yet it can readily be moved transversely thereof.

2. A label-holder for a vertical file sheet with a portion along its upper edge that can be folded down, consisting of a sheet of metal having an upper label-holding portion, and integral means for holding the ends and edges of a label thereon, and a lower portion provided with an integral upwardly extending tongue adapted to project between the fold and the sheet of paper, and a plurality of downwardly extending integral tongues adapted to rest upon the upper edge and fit behind the sheet of paper, whereby the label-holder cannot be removed vertically from the filing sheet and yet is can readily be moved transversely thereof.

3. In a label-holder for a vertical file the combination of a file sheet having a folded portion at its upper end, a label-holder having a plurality of downwardly extending tongues adapted to extend over the upper end portion of said file sheet so that they rest on the folded edge and extend over the back side of said file sheet and pinchingly engage the folded portion with the back side of said holder, and an upwardly extending tongue to said holder that is spaced a less distance away from the back side of said holder than said downwardly extending tongues so it extends upwardly between the folded portion and said file sheet to pinchingly hold said folded portion against the back side of said holder and so the free end of said tongue can engage the fold between said sheet and folded portion to prevent vertical displacement of said holder relative to said sheet.

4. In a label-holder for a vertical file the combination of a file sheet having a portion at its upper end folded downwardly upon said sheet, a label-holder having a plurality of downwardly extending tongues adapted

to extend over the upper end portion of said file sheet so that they rest on the folded edge and extend over the back side of said file sheet and pinchingly engage its folded portion with the back side of said holder, an upwardly extending tongue to said holder that is spaced a less distance away from the back side of said holder than said downwardly extending tongues so that it extends upwardly between the folded portion and said file sheet to pinchingly hold said folded portion against the back side of said holder, and so the free end of said tongue can engage the fold between said sheet and folded portion to prevent vertical displacement of said holder relative to said sheet, an inclined bed plate integral with said holder, and with their connection bent to form a rest for engaging the lower edge of a label, a flange at the top edge of said plate for engaging the top edge of the label, and detents integral with the plate for extending over the ends of said label and detachably holding it on said bed plate.

5. In a label-holder for a vertical file the combination with a file sheet having a fold at its upper edge of a sheet-metal label-holder adapted to be detachably connected to the folded edge of said file sheet said holder including an inclined bed plate integral with the top edge of said holder, and bent at an angle to form a rest on the bottom edge of said plate for supporting a label, a flange at the top edge of said plate for engaging the top edge of the label, and detents adjacent the ends of said bed plate for engaging and detachably holding the label on said bed plate.

6. A label-holder for a vertical file sheet having a folded portion at its upper end, consisting of a label-holding portion and a lower portion bent at an angle to each other, means on said lower portion for mounting said label-holder on said file sheet including a downwardly extending tongue adapted to overlap the upper part of the folded sheet, said lower portion having an upwardly extending tongue adapted to project under the fold of the sheet, said tongues being displaced from the lower portion of the label-holder so as to engage the body of the sheet.

7. A label-holder for a vertical file sheet having a folded portion at its upper end consisting of an upper label-holding portion and a lower portion for mounting said label-holder on said file sheet, the two portions being bent at an angle to each other, said lower portion having an upwardly extending tongue on the rear side adapted to project under the fold of the sheet and prevent vertical separation of the label-holder from the sheet and permit lateral movement thereof.

In witness whereof, I have hereunto affixed my signature.

JOHN T. QUIGLEY. 130
